STEFAN SCHVACHO, OF TRENCIANSKE TEPlice, LAZNE, CZECHOSLOVAKIA

COMBINATION X-RAY RADIATOR

Application filed October 29, 1927. Serial No. 229,692.

The object of this invention is the embodiment into one single apparatus of an X-ray generator, a quartz sun lamp, Finsen lamp, and solus and electromagnetic lamps. At 5 the present time for each lamp a separate unit (apparatus) is required because it is essential to use too absolutely different currents.

The X-ray generator requires high-tension 10 current with constant interruption, while the quartz sun lamp and the others operate on the ordinary low tension house current. For above stated reasons each lamp requires a separate apparatus and equipment, which 15 is costly and requires more room or floor space, thus causing difficulties with constant relocation of the equipment and provides high maintenance.

To eliminate the above stated difficulties, 20 and to make it possible for every physician to own and use all five lamps the apparatus constituting the subject matter of this application has been devised.

This invention eliminates the necessity of 25 five separate units and makes it possible to accomplish in the most perfect way in each case with one apparatus the work of five, due to the switching layout of the two separate well known electric systems of the X-ray 30 generator and the quartz sun lamp, etc., in a combination which makes it possible with one and the same apparatus to operate the X-ray generator, the quartz sun lamp, etc. This is made possible by the layout and arrangement of the switching systems in a close 35 space, in other words in a chamber of small dimensions.

In the accompanying drawing:

Figure 1 is a diagrammatic view representing 40 the apparatus embodying my invention arranged and adapted for use as an X-ray generator; Figure 2 is a similar view with the apparatus arranged and adapted for use in construction with a quartz lamp, Finsen 45 lamp, or electromagnetic lamp.

The fundamental progress which shows the combination of these two circuits is due to the fact that the service distributing board is made in two parts, one switching part and 50 a manipulating distributing board. Through

the arrangement of this switching distributing board it is possible to use or operate on this single apparatus the X-ray generator, the quartz sun lamp, the solus lamp, the Finsen and the electromagnetic lamp, wherefore 55 the work in operating only one apparatus is shortened and the expenses are reduced.

Fig. (1): When used for X-ray generator, on the distributing switching board (not shown in drawing) a two-pole switch (4), is 60 located, which is hooked (connected) to the lower contact clips (11). The current flows as follows: From the circuit through the fuse (5) into the two-pole switch (4); the negative current flows through the clamps (11), 65 into the ammeter (8), and into the inductor (2), the secondary coil (21), through here it proceeds into the interruptor (12). The positive current flows through the clamp (11), from here into the rheostat (6), and 70 into the interrupting switch (13). Across these two connections a voltmeter is inserted (7).

The prime circuit (20) of the inductor (2), is connected to the spark-gap (3). One conductor to clamp (11), and the other conductor through the milliammeter (9), into the other clamp (11). This clamp (11), is separately connected to the single pole switches (10); these are located at proper distances 75 between themselves on the distributing switch-board (which is not shown) and directly connected to conductors (18), of the X-ray lamp (1), therefore as soon as the interrupter (12), switch (13), are connected, 80 the X-ray lamp (1) is lighted.

Fig. (2): When using the combination apparatus for the quartz lamp or the other lamps, we replace the X-ray lamp (1) with 85 the quartz lamp (14), or any other lamp and change the two-pole switch (4), to the upper contacts (16), at the same time we change the single pole switches (10), to the upper contacts (16), and the path of the current 90 will be as follows: From the house circuit the current will flow through the fuses (5), into the double pole switch (4), thence to the clamps (16). Here the positive current goes 95 to the rheostat (15), from here to the clamp 100

(16), of the single pole switch (10) and this is connected to the quartz lamp (14).

The negative current flows from the clamp (16), of the two-pole switch (4) into the clamp (16) of the single-pole switch (10), and thence into the quartz lamp (14). From the rheostat (15), the current of the auxiliary pole flows through the conductor (17), into the quartz lamp (14), or any of the other lamps. As soon as the rheostat (15) handle is connected the quartz lamp or any of the other lamps will be lighted. When not using the combination apparatus all switches must be disconnected.

15 I claim:

A convertible apparatus for the supply of current to an X-ray generator, a Finsen lamp, or quartz lamp, and an electromagnetic lamp, comprising a service distributing board, current supply connections, a two pole switch on said board in circuit with the current supply connections, switch contacts constituting the terminals of separate circuit leads, and arranged in pairs, a transformer, 20 the primary coil of which is in said circuit through one pair of said switch contacts, and a current interrupter in circuit with said primary coil, and constituting a path through which said circuit is completed; a second circuit leading from the second pair of switch contacts through and including the secondary coil of said inductor and having connections adaptable to an X-ray tube, and to the other forms of lamps, the two circuits having 25 their leads and conductors mounted on said distributing board and constituting a unitary system, controllable through said switches arranged and adapted to switch into use alternately high and low tension currents.
